UNITED STATES PATENT OFFICE

2,179,637

GAS PRODUCER

Heinrich Koppers, Essen, Germany, assignor, by
mesne assignments, to Koppers Company, Pitts-
burgh, Pa., a corporation of Delaware

Application April 8, 1936, Serial No. 73,230
In Germany March 22, 1934

2 Claims. (Cl. 126—182)

This invention relates to a gas producer with revolving grate which is provided with openings, through which steam or air can be blown into the fuel charged in the shaft of the gas producer and especially to those gas producers in which the grate openings are connected in pairs or groups to separate distributing chambers individual to the pairs or groups, situated underneath the grate and from which air or steam or a mixture of air and steam is distributed into the openings of the grate.

The main object of my present invention is to provide such improvements in the gas producers that the media, such as air and steam, necessary for gasifying the fuel are uniformly distributed over the whole surface of the grate, quite independently of the differences in resistance to which the reaction gases are subjected in various different areas of the gas producer shaft.

Another object of my invention consists in providing the gas producer with means to permit if required, more steam or another media to be introduced into certain zones of the fuel bed of the gas producer shaft above the grate than into other zones without having, however, any unfavourable influence upon the necessary uniform distribution of air and steam in said other zones of the gas producer shaft.

The inventor has found, in connection with a revolving grate gas producer, that the degree of the pressure necessary for forcing the steam or the steam-air mixture through the grate openings into the fuel above the grate is quite different in the middle of the grate from that at the periphery of the grate.

Furthermore, the inventor has ascertained that the surface of the revolving grate can be divided up into concentric circular zones of different pressures with regard to pressure at the openings of the grate. The pressure drop in each of these zones is uniform whereas the pressure drop from one zone to another alters quite considerably.

The invention based on these tests consists in connecting the grate openings in various circular zones of the revolving-grate gas producer in pairs or groups to distributing chambers, which are separate from one another, and adjusting the quantity as well as the pressure of the steam or of the steam-air mixture respectively supplied to the various distributing chambers according to the pressure drop in the various grate zones, thus obtaining a uniform distribution of the steam or of the steam-air mixture over the gas producer shaft.

Furthermore, the present invention consists in

connecting individual sectors of the grate of the gas producer to a special steam supply pipe line in such a way, that these sectors can be charged with more steam than the other parts of the grate. This has the effect that at a full revolution of the revolving grate, each part of the fuel bed above the grate is supplied to a great extent with steam once or several times for a short period. By means of the comparatively large quantity of steam which penetrates into the fuel at these points, the temperature of the fuel is suddenly reduced and thus the larger ash pieces which may be formed in the fuel bed are broken-up.

Still further objects of my invention will be apparent from the following description of a preferred embodiment of my invention on the line of the accompanying drawings in which:

Fig. 1 is a vertical section through the lower portion of a gas producer.

Fig. 2 is a plan view partly in horizontal section on line II—II through the grate of the gas producer illustrated in Fig. 1, on a larger scale.

The gas producer as illustrated on the drawings receives at its upper part the fuel which is to be gasified in shaft 1, which is formed by a double wall-water-cooled shell 2. The space 3 between the walls of the shell 2 takes a suitable cooling liquid for preventing a glowing of the inner wall of the shell. The double shell 2 is provided at the bottom with an essentially cylindrical extension or ash apron 4 which projects freely into the ash pan 5, being arranged underneath the lower shaft opening.

Underneath the bottom 6 of the ash pan, there is provided a number of roller bearings 7 which are arranged on the foundation 8 of the gas producer. The bottom 6 of the ash pan is fitted with a rim 9, lying on the rollers 7. The edge of the ash pan 6 has a worm-wheel-like gear 10, into which engages a worm 11, which is likewise supported on the foundation 8. This worm is connected with an actuating gear not shown on the drawings. It is clear, that by means of the worm 11, the ash pan can be rotated on the rollers 7. Horizontal rollers 12 prevent the sliding-off of the rim 9 of the ash pan during the rotation of the rollers 7.

The grate is arranged on the ash pan. This grate consists of an approximate cylindrical casting 13, on which is arranged a conical hood 14. In the latter there have been provided openings 15, necessary for admitting steam or air or a steam-air mixture into the shaft 1. The top 16 of the grate hood 14 is likewise fitted with chan-

nel-like bores 17, leading from the space underneath the grate into the gas producer shaft.

Several boxes 18 have been arranged underneath the grate hood which are formed by partition walls 19 and bottoms 20. A number of openings 15 of the grate hood lead into each box 18, whereas in the bottom 20 of every box 18 there is provided an opening 21, the free section of which can be altered as desired.

10 The grate hood itself is, as shown on Fig. 2, composed of various sectors 14a, which are grouped around the star-like base 17a of the grate top 16. The openings 15 of the grate hood are preferably shaped in the form of slots, 15 which are inclined upwards (see the lower half of Fig. 2) and covered at the outside by roof-like projections 22. The inclined position of the slot openings 15 in connection with the roof-like projections 22 prevents the ash or the fuel from 20 penetrating if the grate during the operation is turned in the direction of the arrow 23. (Fig. 2.) The various sections of the grate hood are connected with one another by screws or in another suitable manner and they are fastened 25 to the cylindrical casing 13 of the grate by screws 24.

The bottom 6 of the ash pan 5 is provided in the center, i. e., in the range of the grate, with an opening 25, which has a cylindrical gas-sealing edge extension 26, extending downwards for freely rotating in a sealing cup 27, provided underneath the ash pan. The sealing cup 27 is formed by two concentric pipes 28. The pipes 28 are placed on a bottom part 29, lying on the 35 foundation of the gas producer. The space between the pipe pieces 28 is filled with a suitable liquid for sealing and the level is such that the liquid column which can be kept in the space is balanced by the pressure to be maintained inside the grate casing and the lower edge of the projection 26 always dips into the liquid. At the inside, the interior of the pipe 28 is lined with a heat insulating material for preventing any unsuitable heating of the sealing liquid.

40 Below the bottom 29 of the sealing cup there is provided a passage 30, to which is connected the steam-and-air supply pipe 31.

Due to the sealing cup 27, it is therefore possible to blow the steam or air or a steam-air mixture underneath in every position of the grate at such a pressure which is necessary for penetrating the ash or fuel layer in front of the openings 15 of the grate.

If the openings 21 in the bottoms of the distributing chambers 18 are made such a size that a certain reduction of the steam-air flow on entering the distribution chambers 18 can take place, the pressure reserve permits a supply uniformly to the various distributing chambers of steam and air even if the openings into one of the chambers are more plugged-up with ash or fuel than the openings into the other chambers. At two points, lying preferably opposite, the openings of the grate are connected to distributing chambers which are to supply auxiliary steam and air.

70 For this purpose the openings 21 of these distributing boxes are connected with the feeding pipes 32, which run into a common supply pipe 33, being arranged inside the main stem pipe 31. The pipe 33 has an extension 34 rotatable in a sealing cup 35. This cup is formed by an elongation 31a of the main steam pipe and by a concentric pipe piece 36, resting on the bottom piece 37, which on its part is fastened

5 on the foundation 8 of the gas producer. An auxiliary air main 38 is connected with the pipe 36. A steam pipeline 39 is provided in the line 38, reaching near below the branches 32 of the pipe 33 and outside the gas producer it protrudes through the pipe 38. The pipe 38 supplies the air and it is governed by a shut-off and regulating valve. The pipe 39 supplies the steam and is likewise governed by a shut-off and regulating valve. For simplicity's sake, these valves are 10 not shown on the drawings.

Analogous to the sealing cup 27, the sealing cup 35 is formed so that even at a maximum pressure of steam or of the steam-air mixture in the pipe 33 the sealing liquid does not sink 15 below the bottom edge of the pipe extension 34 so that, therefore, the inside of the pipe 33 is permanently sealed against the pipe 31. The connection of one or two sectors of the grate hood to a special steam supply pipe renders it 20 possible to introduce if required a larger quantity of steam through the openings 15 of these sectors than through the other openings 15. The larger quantity of steam suddenly cools down the ash in front of the sector and on account 25 of the sudden cooling-down the larger ash pieces are crushed which may have been formed so that they can be removed, without causing any trouble, through the space between the lower edge of the gas producer shaft 4 and the ash 30 pan 5. Since at one revolution of the grate, all parts of the fuel bed above the grate are successively subjected to an additional larger quantity of steam, there results a uniform destruction of all ash pieces over the whole section 35 of the grate.

The arrangement of a special steam or steam-air mixture supply pipeline for one or several sectors of the grate is of great advantage for a uniform removal of ash and slag from the gas 40 producer shaft and is also advantageous in event, when the remaining grate openings are not connected to special distributing chambers for steam and air.

As already mentioned before, it is essentially 45 important for a successful carrying out of the invention, that the openings 21 of the distributing chambers 18 are suitably adjusted, so that between the inner distributing chambers and the space underneath the grate there exists a suitable pressure drop. The adjustment of the free 50 section of the opening 21 can be made as desired, but preferably in such a way that small slides 40 are pushed before a part of the opening.

The slide 40 is then fastened in the desired 55 position by means of screws 41 or in another suitable manner. It is of course understood, the gas producer can be constructed in other respects in any desired way and is provided with usual contrivances for good operation, which for simplicity's sake have not been fully detailed on the drawings.

I have described my present invention in connection with the preferred embodiment thereof, but my invention is limited in all its aspects to 65 the mode of carrying out as described and shown, since the novel features of the invention may be variously embodied within the scope of the following claims.

I claim:

1. A gas producer having a revolving grate with openings for diffusion of aeriform fluid into the producer fuel bed zone, arranged in annular zones of different level, the openings in the respective zones of the grate being con- 75

5 nected in groups with distributing chambers individual thereto and arranged beneath the diffusion openings, and each of said distributing chambers being connected by ports to a common aeriform fluid supply chamber, the free section of the connecting ports between the distributing chambers and said common supply chamber having such dimension that a pressure drop in the aeriform fluid current will occur as it enters each of the distributing chambers from the common chamber, and an auxiliary aeriform fluid supply means for concurrently feeding aeriform fluid to the distributing chamber of a localized sector of the grate independently of the supply of aeriform fluid simultaneously from the common chamber to the other distributing chambers of the grate.

10 2. A gas producer having a revolving grate with openings for diffusion of aeriform fluid into the producer fuel bed zone, arranged in annular zones of different level, the openings

15

20

in the respective zones of the grate being connected in groups with distributing chambers individual thereto and arranged beneath the diffusion openings, and each of said distributing chambers being connected by ports to a common aeriform fluid supply chamber, the free section of the connecting ports between the distributing chambers and said common supply chamber having such dimension that a pressure drop in the aeriform fluid current will occur as it enters each of the distributing chambers from the common chamber, and an auxiliary aeriform fluid supply means for concurrently feeding aeriform fluid to distributing chambers for several zones of diametrically opposite localized sectors of the grate independently of the supply of aeriform fluid simultaneously from the common chamber to the other distributing chambers of the grate.
